[57] **CLAIM**

The ornamental design for a wall-mounted animal feeding ledge with bowl ports and pop-up housing for a can opener, as shown and described.

DESCRIPTION

FIG. 1 is a perspective view of a wall-mounted animal feeding ledge with bowl ports and pop-up housing for a can opener showing my new design;

FIG. 2 is a top plan view thereof;

FIG. 3 is a right side elevational view thereof showing the can opener housing in raised position;

FIG. 4 is a left side elevational view;

FIG. 5 is a bottom plan view thereof;

FIG. 6 is a rear elevational view showing the can opener housing in raised position; and,

FIG. 7 is a front elevational view thereof.

The broken lines are for purposes of illustration only and form no part of the claimed design.
